[57] ABSTRACT

A refuse compactor having an electrically controlled heat motor compacting means characterized by a refuse compacting ram movable in a main chamber which is subdivided by a resilient sleeve into concentric outer and inner annular cavities with the outer cavity containing thermally responsive material and the inner cavity containing hydraulic fluid. As the thermal material expands under the influence of a heating element therein the hydraulic fluid is compressed within the sleeve to force the ram in a waste compacting direction. A regulating valve controls the flow of the hydraulic fluid to and from an accumulator in conjunction with the energization of the heating element providing substantially instant return of the ram to its full cycle position.

HEAT MOTOR POWER UNIT FOR DOMESTIC WASTE COMPACTOR

This invention relates to waste compactors in general and more particularly to an electrically controlled heat motor compaction means for a domestic waste compactor.

The prior art is replete with compacting devices having ram plates driven by various motive means such as electric motors, hydraulic fluid pumps, and air pressure compaction bags. For various reasons such as cost, maintenance and reliability none of the above systems have proved entirely satisfactory.

It is an object of this invention to solve the problem by providing a refuse compactor incorporating an integrated electrically controlled heat motor and hydraulic fluid drive system allowing substantially instant return of the compacting ram after each compaction cycle.

A more specific object of this invention is provision of a domestic refuse compactor in which a compaction electrically controlled heat motor has a refuse compacting ram movable in a main chamber which chamber is subdivided by a resilient sleeve into concentric outer and inner annular cavities in which the outer cavity contains thermally responsive material and the inner cavity contains hydraulic fluid such that as the thermally responsive material expands under the influence of a heating element therein the hydraulic fluid is compressed to initiate a waste compacting cycle whereby after the refuse is compressed regulating valve means causes the hydraulic fluid to return to an accumulator allowing substantially instant return of the ram to its full cycle cooling position.

Further objects and advantages of the present invention will be apparent from the following description, reference being had to the accompanying drawings wherein a preferred embodiment of the present invention is clearly shown.

In the drawings:

FIG. 1 is a perspective view of a domestic refuse compactor embodying the invention;

FIG. 2 is a rear elevational view of the refuse compactor with the rear panel removed;

FIG. 3 is a broken longitudinal sectional view of the compaction heat motor constructed in accordance with the present invention, the ram being shown in its upwardly biased position at the start of a cooling cycle;

FIG. 4 is a fragmentary sectional view of the regulator valve taken on line 4-4 of FIG. 3 together with a schematic wiring diagram of the control system.

As shown in FIGS. 1 and 2, the trash compactor 10 includes a vertically elongated cabinet 12 having side walls 14, a rear wall (not shown) and an upper front wall 16 provided with a lower opening 18 in which a front access door 20 is connected by hinges 22 to the inturned flange 23 of the left hand side panel 14. A releasable door latch 24 and keeper 26 are provided between the door 20 and the inturned flange 25 of the right hand side wall 14 so that the door can be latched closed but can be selectively opened when the latch is released as shown in FIG. 1. An on-off push button electrical switch 30 is mounted on the front wall 16 of the cabinet such that operation of the compactor may be manually controlled by the switch.

The compactor casing 10 includes a top wall 32 and a base wall 33 supporting an angle iron framework 34 comprising a pair of spaced horizontally disposed top 36 and bottom 38 angle members on each side and run-

ning the length of the cabinet interconnected by a pair of forward vertical angles, one of which being shown at 40 in FIG. 1, and a pair of rear vertical angles 42 (FIG. 2). The framework further comprises a pair of transverse upper and intermediate horizontal braces indicated at 44 and 46, respectively in FIG. 2 showing the framework rigidly assembled by suitable means such as by bolt members shown.

Compaction motive means, indicated generally at 50 in FIGS. 1 and 2, is provided for compressing refuse material. The compaction means is shown vertically oriented between the upper braces 44 and the intermediate braces 46 of the casing 10 and includes a lower elongated main cylinder 52 provided with a ram member 54 extending axially of the main cylinder so as to pass through opening 51 in a sealed manner by O-ring seal 55 and is shown at its full cycle position with ram member 54 raised to its fullest extent.

The ram member 54 carries on its lower extremity a ram plate or platen 56 suitably affixed thereto such that the ram plate can be vertically raised or lowered to compress refuse located in a container which, in the disclosed embodiment, is an open-top rectangular metal container 58 slidably positioned on the bottom wall between the angles 38. In the form disclosed the container 58 prior to its use is lined with a disposable bag 60 having a top cuff 62 turned over the top edge of the container and of a sufficient length so that the bottom of the bag rests upon the bottom of the container. The container 58 is of a rectangular configuration which allows the rectangular ram plate 56 when descended on the ram to be introduced into the container to compress the refuse placed therein.

As seen in FIGS. 1 and 2 the compaction motive means 50 is in the form of an integrated heat responsive thermal motor and hydraulic fluid transmitting actuator having means for biasing the output ram 54 in its upper full cycle position which in the preferred form 40 comprise a plurality of elongated resilient spring members. In the disclosed embodiment the ram plate 56 and ram 54 are resiliently urged in an upward direction by four coil tension springs 64 secured in quadrature, one of the springs being suitably connected adjacent each corner of the ram plate 56 by a loop at one of its ends engaged around an eyelet 65 welded to the upper surface of the ram plate. In the preferred form suitable clips are struck from each end of horizontal top angles 44 such that the springs 64 are stretched in tension 45 when the piston is driven downward. It will be appreciated that the coil springs 64 also serve to restrict rotary movement of the ram plate during its travel.

The main cylinder 52 is closed by threadedly receiving upper cover member 66 and lower cover member 68, sealed by O-ring 69, to define a compression chamber in which is disposed a hollow boot 70 formed of a resiliently flexible elastomeric material such as soft rubber or the like. The boot 70 comprises a concentric cylindrical sleeve 72 having a diameter substantially less than the inside diameter of the cylinder establishing an outer cylindrical cavity 73 and an inner cylindrical cavity 74. The wall of the sleeve 72 merges at its upper end with a radially extending flange 75 having an integral annular O-ring seal 76 on its outer periphery for reception within annular groove 78 of the upper cover member 66 such that when the threads are taken up a fluid tight seal is provided therebetween.

The lower end of the sleeve 72 is positioned between an upwardly extending hub member 80, located on the inner face of the bottom cover 68, and vertically extending return spacer flange portion 82 of a perforated tube 84 positioned in concentric relation with ram 54. The tube 84 extends the full height of the cylinder 52 with its upper end received in a downwardly extending cylindrical boss 86 on the underside of the upper cover member 66.

The outer cylindrical cavity 73 provides a first pressure chamber that is filled with a heat fusible material, such as paraffin wax, having a designation N-paraffin wax C₃₆, which fuses and expands at a predetermined temperature to produce hydraulic pressure changes within the outside cavity 73. The inner cavity 74 provides a second pressure chamber that contains hydraulic fluid such as oil and upon the expansion of the heat fusible material a resultant compression force is exerted on the resilient sleeve 72 thereby causing the hydraulic fluid to transmit the pressure created in the outer cavity to the ram 54.

As the pressure increases in the outer cavity 73 the fusible wax material exerts compressive forces at all points on the sleeve 72 such that the forces circumferentially and radially compress the sleeve 72 uniformly toward the output ram 54. The hydraulic fluid pressure in cavity 74 causes the ram member 54 to be forced downwardly out of the main cylinder and apply a considerably pressure through the ram plate 56 to compact refuse in the container. In the disclosed form of the invention the working hydraulic pressure developed in cavity 74 is about 9000 pounds per square inch such that with a ram diameter of the order of 0.60 inch there is produced a resultant ram force of about 3,000 pounds.

Accumulator means are provided in the form of a secondary cylinder 90 having a cup-shaped cylindrical cap member 92 telescopically mounted on peripheral shoulder 88 of cover member 66 and sealed thereto by O-ring 93. The upper cover 66 has a stem 95 extending axially of the cylinder 52 and passing through concentric opening 94 into dished portion 96 of the cap 92 whereby the cap is retained in sealed relation on the cover 66 by a snap ring 97.

As seen in FIG. 3, slidably positioned around the vertical stem 95 is a cup-shaped spring loaded accumulator piston 100 whose outer circumferential wall 102 is slidably movable in an axial direction within the cap member 92 in a sealed manner by means of outer O-ring seal 103 and inner O-ring seal 104. The cup-shaped piston 100 has a central hub portion 105 which extends vertically to engage the dished portion 96 of the cap 92 to limit its upward travel. The piston 100, shown at its full cycle position, is axially movable on the stem 95 and is biased in a downward direction to force the hydraulic fluid therein into the main cylinder 52 by compression coil spring 106 whose upper end engages the closed end of the cap member 92 and whose lower end surrounds piston central annular trunnion 107 resting thereon. The blind end of the piston 100 and the upper cover member 66 define a fluid reservoir chamber 109 of the spring loaded accumulator. Suitable piston position switch means are provided which in the disclosed form include an L-shaped arm 108 extending upwardly from the upper edge of wall 102 through aligned slot means in the cap 92 operative to depress and close a micro switch 127 to sense the fully

extended downward travel of piston 100 for a reason to be explained.

A heating element in the form of heating coil 110 having a mean diameter of about 2.0 inches is concentrically located in the main cylinder 52 so as to be embedded in the wax material while the opposite ends of the heating coil are connected to the exterior electrical terminals 112 and 114, which terminals are in turn connected to an appropriate source of electrical current and compactor control means to be described.

Referring to the schematic diagram shown in FIG. 4, terminals L₁ and L₂ are adapted to be connected to a suitable source of electric power, such as 110 volt alternating current. In one line 120, the on-off cut-out relay switch 30 has a push-button contact member 121 which when depressed energizes a solenoid 123 in electrical series with L₁ via line 120 and L₂ via closed switch 132 to hold contact member 121 closed. Member 121 is mechanically linked to contact bridging member 124 which closes a circuit by line 125 through the closed contact 126 of depressed micro switch 127 because of the extended spring biased position of the piston 100. Line 128 is connected to the solenoid 129 of a relay 130 for a shuttle control two-way valve 136. The solenoid 129 is suitably linked by shuttle rod 131 to a pair of double-pole, single throw switches 132 and 133 of the relay 130. The normally closed switch 132 has one contact connected by line 135 to contact 121 of push button switch 30 and switch 132 has its other contact connected by line 134 to L₂. The normally open switch 133 is electrically connected by one contact to heating element 110, which is in series with a temperature limiting thermostat 139 while the other contact of switch 133 is connected to solenoid 129.

As seen in FIG. 4 valve 136 includes a transversely extending valve bore 140 that slidably receives a valve shuttle 142 therein. The bore 140 is closed at its enlarged end by plug member 143 while the opposite end of the bore 140 remains open to receive relay rod 131 therein suitably affixed to one end of the shuttle. The shuttle 142 is provided with undercut land portions 144 and 146 separated by O-ring seal 145 and the annular groove portion 148 which is dimensioned to seat resiliently biased detent 150 urged into the groove 148 by compression spring 151 to retain the shuttle 142 in a closed position to prevent movement of hydraulic fluid through passages 137 and 138. Annular land portions 152 and 153 of the shuttle 142 have an annular groove therebetween for seating O-ring seal 154 and are normally disposed in enlarged bore 155. The undercut lands 144 and 146 are dimensioned so as to be slidably disposed in the bore 140. In the disclosed form the bore 140 has a diameter of about 0.250 inches, the undercut portions 144 and 146 have a common diameter of about 0.248 inches and the large bore 155 has a diameter of about 0.270 inches to slidably receive the lands 152 and 153 whose diameter is about 0.268 inches.

When the valve shuttle 142 is in its closed position, shown in solid lines in FIG. 4, fluid under pressure is free to pass from the inner cavity 74 of the heat motor through passage 138 into bore 140 and thence into bore 155 where it is blocked by elastomeric O-ring seal 154 in sealed engagement with bore 155. During this pressure build-up the reciprocal ram 54 is axially driven downwardly in its refuse compacting stroke against the ram biasing means of springs 64. The fluid pressure differential between the larger lands 152, 153

and reduced diameter undercut portions 144, 146 causes the shuttle 142 to be urged in the direction of the arrow under a working or low-pressure condition in cavity 74. The resulting force acting on the shuttle 142 is not sufficient to overcome the biasing force of the spring 151 so that the shuttle 142 maintains its closed solid-line position of FIG. 4.

Upon the increase of the fluid pressure above a predetermined or trigger pressure in inner cavity 74, which in the instant form is of the order of 9000 psi, the resulting axial force on the shuttle 142 will overcome the spring bias 151 and detent 150 causing the shuttle 142 to move to its dashed line open position 142 thereby unseating and repositioning O-ring 154 in large bore 162. The fluid in cavity 74 under pressure from collapsing sleeve 70 is free to pass through passage means 138 and 137 into the accumulator chamber 109 allowing the biasing springs 64 to instantly initiate return or travel of the ram.

The sequence of operation of the waste compactor is as follows: With the ram 54 in its raised or full-cycle position the wax cooling period starts. As the wax material cools and contracts the hydraulic fluid in chamber 109, under the spring bias pressure of the piston 100, is forced to flow back through passage 137, the open valve 136 and passage 138 into the main cylinder cavity 74. Accumulator position micro switch 127 senses the downward or extended position of the piston 100, wherein the fluid or oil has re-filled the cavity 74 of the main cylinder by being set by arm 108 to its closed position. After a quantity of trash is deposited in the container 58 the operator depresses push button 121 energizing the solenoid 129 and causing the shuttle 144 to be moved to its closed position energizing heater means 110 via the switch 133 to initiate a new compaction cycle.

It will be appreciated that by virtue of applicants' novel arrangement an integrated electrically controlled heat motor and hydraulically actuated output ram provide a downward force on ram plate or platen 56 sufficient to compact domestic refuse material in container 58 while attaining a rapid upward return of the ram, obviating the need for a delayed cooling period during which the wax material contracts and solidifies. The disclosed form of the invention utilizes approximately 26 cubic inches of fusible wax material which undergoes an expansion of the order of 17 percent by volume upon being heated. Thus, the instant ram return results from the unique combination of an accumulator regulated hydraulic fluid and thermally expansible heat motor systems which coact to transmit the pressure from the thermally responsive wax material to the output ram via an incompressible liquid thereby allowing for rapid upward return of the ram by means of the regulating valve and accumulator circuitry.

In addition it should be noted that the rapid upward return is also assisted by having the temperature responsive wax material in cavity 73 out of contact with the ram so that the wax material will not impart a large frictional drag on the ram 54. The hydraulic fluid serves as a lubricant to minimize the sliding frictional drag of the ram 54.

It should be noted that while the preferred embodiment of the heat motor discloses housing means in the form of columnar main or primary cylinder 50 and secondary accumulator cylinder 90 the invention contemplates alternative forms of housing means. For exam-

ple, the accumulator cylinder 90 could be mounted alongside of the primary cylinder 90 with suitable passage means effecting hydraulic fluid communication therebetween without departing from the scope of the invention.

While the embodiment of the present invention constitutes a preferred form, it is to be understood that other forms might be adopted.

I claim:

- 10 1. A force transmitting thermal heat motor for a compactor comprising, housing means containing main and secondary fluid-pressure cylinders, an elastic sleeve disposed concentrically in said main cylinder forming inner and outer annular fluid-tight cavities, said main cylinder having an opening in one end in communication with said inner cavity, a ram positioned for slidable fluid-tight movement in said opening in a reciprocal manner, means for biasing said ram into said main cylinder, platen means on the free end of said ram, hydraulic fluid within said inner cavity and a thermally sensitive expansible mass of material within said outer cavity, passage means connecting said main and secondary cylinders and effecting hydraulic fluid communication therebetween, a piston in said secondary cylinder, yieldable means for biasing said piston in a direction tending to force hydraulic fluid from said secondary cylinder into said primary cylinder via said passage means, control means including valve means in said passage means for supplying hydraulic fluid under pressure selectively between said secondary cylinder and said inner cavity, heating means disposed in said outer cavity and having terminals for receiving an electrical current from a source outside said housing means, whereby the energization of said heating means causes the expansion of the mass of material and resultant pressure on said sleeve adapted to compress said sleeve and transmit the pressure to the hydraulic fluid in said inner cavity to move said ram outwardly from said main cylinder such that said platen means thereon applies a compaction force to the material, means biasing said valve means so as to normally close said passage means, said valve biasing means being responsive to a predetermined amount of hydraulic fluid pressure within said inner cavity opening said passage means thereby permitting the hydraulic fluid to return to said secondary cylinder, and said control means operative in response to the opening of said valve means to deenergize said heater means such that said ram is readily returned into said main cylinder by said ram biasing means.
- 20 2. In a refuse compactor having a support, means for holding refuse to be compacted in a preselected compacting position, a platen member, heat motor drive means carried on said support for driving said platen member into said refuse-holding means to compact refuse received therein, said heat motor drive means including main and secondary fluid-pressure cylinders, an elastic sleeve disposed concentrically in said main cylinder forming inner and outer annular fluid-tight cavities, said main cylinder having an opening in one end in communication with said inner cavity, a ram positioned for slidable fluid-tight movement in said main cylinder opening in a reciprocal manner, said platen supported on said ram, resilient means for biasing said ram into said main cylinder, hydraulic fluid within said inner cavity, thermally sensitive expansible material within said outer cavity, passage means connecting said main and secondary cylinders and effecting hydraulic

- 65

fluid communication therebetween, a piston in said secondary cylinder, yieldable means for biasing said piston in an extended direction tending to force hydraulic fluid from said secondary cylinder into said main cylinder via said passage means, control means including a valve body having a cylindrical bore interrupting the flow of hydraulic fluid through said passage means, a valve shuttle element slidably disposed within said bore for movement selectively opening and closing of said passage means, means biasing said shuttle element in its closed position such that when said valve shuttle element is moved to its open position communication is established through said passage means, heating means disposed in said outer cavity and having terminals for receiving an electrical current from a power source, whereby the energization of said heating means causes the expansion of the material in said outer cavity and resultant pressure on said sleeve adapted to compress said sleeve and transmit the pressure to the hydraulic fluid in said inner cavity to move said ram outwardly from said main cylinder, said valve shuttle being responsive to the increase of the fluid pressure above a predetermined amount to overcome said shuttle biasing means and move said valve shuttle element to its open position and thereby permitting the hydraulic fluid to flow into said secondary cylinder and thereby allow said ram biasing means to readily return said ram into said main cylinder, said control means including normally open heater switch means responsive to the movement of said valve shuttle element whereby said heater switch means is closed to energize said heater means only when said valve shuttle element is in its closed position, said control means including solenoid means operative for moving said valve shuttle element to its closed position upon the return of said piston to its extended position.

3. In a refuse compactor comprising, a support frame, a cabinet enclosing said support frame having door means covering a lower access opening in said cabinet, means for holding refuse to be compacted in a preselected compacting position within said lower opening, a platen member, heat motor drive means carried on said support frame for driving said platen downwardly into said refuse-holding means to compact refuse received therein, apparatus for operating said ram comprising: main and secondary fluid-pressure cylinders mounted on the support, an elastic sleeve disposed concentrically in said main cylinder forming inner and outer annular fluid-tight cavities, said main cylinder having an opening in one end in communication with

5 said inner cavity, said ram positioned for slidable fluid-tight movement in said opening in a reciprocal manner, resilient means for biasing said ram into said main cylinder, hydraulic fluid within said inner cavity, thermally sensitive expandible material within said outer cavity, 10 passage means connecting said main and secondary cylinders and effecting hydraulic fluid communication therebetween, a piston in said secondary cylinder, yieldable means for biasing said piston in an extended direction tending to force hydraulic fluid from said secondary cylinder into said main cylinder via said passage means, apparatus control means including a valve body having a cylindrical bore interrupting the flow of hydraulic fluid through said passage means, a valve shuttle element slidably disposed within said bore for movement selectively opening and closing of said passage means, means biasing said shuttle element in its closed position such that when said shuttle is moved to its open position communication is established through 15 said passage means, heating means disposed in said outer cavity and having terminals for receiving an electrical current from a power source, whereby the energization of said heating means causes the expansion of the material in said outer cavity and resultant pressure on said sleeve adapted to compress said sleeve and transmit the pressure to the hydraulic fluid in said inner cavity to move said ram outwardly from said main cylinder, said valve shuttle being responsive to the increase of the fluid pressure above a predetermined amount to overcome said shuttle biasing means and move said valve shuttle to its open position thereby permitting the hydraulic fluid to flow into said secondary cylinder, said control means including a relay having a solenoid operative when energized to move said valve 20 shuttle element to its closed position, said solenoid connected in electrical series with a start switch, normally open piston position switch means connected in electrical series with said start switch responsive upon said piston reaching its extended position to close and thereby upon the closing of said start switch to energize said solenoid to move said valve shuttle element to its closed position, and normally open heater switch means responsive to the movement of said valve shuttle to its closed position to close said heater switch means and energize said heater means to thereby initiate a refuse compaction cycle.

4. The refuse compactor of claim 3 wherein said secondary cylinder is mounted on the upper end of said main cylinder in axially aligned columnar fashion.
